SPARK INDICATOR AND CONTROLLER

Alexander A. Guziel and Arnold Kerr,
Hollywood, Calif.

Application June 3, 1932, Serial No. 615,155

1 Claim. (Cl. 175—183)

The present invention relates in general to spark controlling and indicating means for internal combustion engines and more particularly to a spark indicating detector for automobiles. 5 The primary object of the invention is to provide a simple and efficient spark detecting device which visibly indicates the action of each individual spark plug of an engine and which may readily and easily be attached to the instrument board of an automobile for continuous observation from the front seat thereof.

Another object of the invention is to provide a spark plug detecting device with adjustable means for intensifying the sparking action of the 15 plugs thus temporarily securing satisfactory running conditions until a defective plug can be conveniently replaced or repaired.

Still another object of the invention is to provide a spark plug detecting device of the kind 20 referred to above, having sparking gaps corresponding to the individual spark gaps for each of the spark plugs of the engine, the sparking gaps of the detector being connected in series with the spark plugs, and provided with means 25 to enlarge or decrease their spark gaps, and thus correspondingly intensify the sparking of the plugs.

With these and other objects in view the invention consists in the construction and novel 30 combination of parts fully described hereinafter, illustrated, in the accompanying drawings, and pointed out in the claims appended hereto, it being understood that various changes in the form, proportion, size and minor details of construction within the scope of the claims may be 35 resorted to without departing from the spirit of the invention.

In the drawings, wherein we have shown an exemplified form of the spark controlling and 40 indicating device according to the invention:

Figure 1 is a front elevation of the spark controlling and detecting device to be used with specially constructed spark plugs;

Figure 2 is a sectional view on line 2—2 of 45 Figure 1;

Figure 3 is a sectional view of one of the spark plugs to be used with the device shown in Figures 1 and 2;

Figure 4 is a front elevation of a modified spark 50 controlling and detecting device to be used with the common spark plug;

Figure 5 is a sectional view on line 5—5 of 55 Figure 4;

Figure 6 is a view of an electrical diagram showing the hook up of the spark controlling and

detecting device according to Figures 1 and 2 with the ignition circuit of an automobile; and

Figure 7 is a view of an electrical diagram showing the hook up of the spark controlling and detecting device according to Figures 4 and 60 5 with the ignition circuit of an automobile.

The spark controlling and detecting device A illustrated in Figures 1 and 2 is designed for indicating and controlling spark plug action of a six-cylinder engine. For such purpose a circular 65 hard rubber or bakelite base plate 2, carrying six contact members 3, equally spaced from each other about the axis of the plate is suitably mounted upon the instrument board 1 of an automobile, not shown. Contact members 3 extend through 70 the base plate 2 and are threadedly connected at their inner ends to hollow tubular contact members or connecting tubes 5 adapted to frictionally embrace and support metal contact shoes 6, which shoes are sleeved upon and electrically connected 75 with lead wires 7 for the spark plugs 8, see Figure 6. Nuts 60 positioned in countersunk portions of base plate 2 are employed to secure the contact members 3 to the base plate. The outer ends of contact members 3 project beyond the face of base 80 plate 2, and thence through a cover plate 61 of insulating material for cooperation with a corresponding number of electrical contact members 9, rotatably arranged with respect to the base plate. Thus contact members 9, integrally formed with 85 or mounted upon the periphery of a metal plate 14, extend through the circumferential flange 10 of a manually operable disk 11, rotatably mounted on the cover plate by means of a threaded stem 12, disk 11 being recessed at its inner face to accommodate plate 14. Metal plate 14, contacts with stem 12, which stem extends through aligned central openings 13 in base plate 2, cover plate 61, metal plate 14, and operating disk 11, and carries 90 at its end a tubular contact member 16 adapted to 95 be electrically connected with the lead wire 13' of the coil C of the ignition system of an automobile, see Figure 6.

The spark plugs 8 used with a device as described above are preferably of the type shown in 100 Figure 3 and include two electrodes 17 and 18 embedded in a porcelain core 19, in turn rigidly mounted in the externally threaded metal shell or casing 20 for screw connection with the cylinder block (not shown). The lower ends of the electrodes 17 and 18 extend through the bottom face 21 of core 19 to form the spark gap 31, and at their upper ends extend into insulated cap member 63 where they are attached to laterally disposed posts 23 and 24 respectively, which posts carry 110

thumb nuts 25, 26 for making electrical connections through wires 64.

The control and detecting device A is connected in series with all the spark plugs 8, see Figure 6 5 wherein the ignition circuit of an automobile is diagrammatically shown. This circuit includes a battery B, a coil C, a distributor D, the spark plugs 8 and the spark controlling and detecting device A. When in operation the current flows from battery B through coil C, which coil as generally known changes the low voltage current to a high tension current. This current then flows through lead wire 13' into distributor D and is in succession and timely distributed to the respective spark 10 plugs 8, and thence to the respective contact members 3 of detecting device A and finally, after jumping the visible sparking gaps 65 between contact members 3 and contact members 9 passes through the ground (the motor body not shown) 15 back to coil C. The extent of gaps 65 can be readily regulated by rotating disk 11 in an appropriate direction, a knob or handle 30 being formed on the disk for this purpose, it of course being understood that any increase in the width of 20 sparking gaps of the detector will result in a corresponding increase in the intensity of the spark at the plug gaps 31. The operator may therefore readily adjust the sparks of spark plugs 8 to the desired intensity while observing proper functioning of his plugs and thus prevent missing of one 25 or more cylinders due to accumulation of carbon and oil at the points of one or more plugs. If desired he may start his machine with intensified sparks and thereafter when the engine is warmed up reduce the intensity of the sparks. The action 30 of the ignition circuit may be under continuous observation, or if so desired the controlling device may be short circuited by turning disk 11 until contact members 3 and 9 engage each other so 35 that sparking at the controlling device is eliminated.

The controlling and detecting device may also be used to start the engine by creating an explosion in that cylinder which is ready for the ignition spark and the spark plug of which at this time has been switched into the ignition circuit by the distributor of the engine. Thus, by turning disk 11 shortly before switching off the engine until contact members 3 hit stop member 52 the gaps 40 between contact members 3 and 9 are widely opened and therefore no sparking can occur. Coil C will then become loaded and will act as a loaded condenser. Rotation of disk 11 in an opposite direction to that just described decreases the resistance between contact members 3 and 9 and causes the spark plug of that cylinder which is ready for firing, to fire when the ignition is switched on. Of course this method of starting the engine is not possible when the engine is very cold. 45 A controlling and detecting device similar in principle to the device A may be used with the standard spark plugs now generally in use. Such a device is disclosed in Figures 4 and 5 which show a controlling and detecting device G also designed for a six cylinder engine. Thus the circular hard rubber or bakelite base plate 32 carries six contact members 33 equally spaced from each other about the axis of said base plate and

electrically connected with their rearwardly extending ends to hollow tubular contact members 34, for connection with lead wires 35. The forwardly extending ends of contact members 33 are 80 rectangularly offset at 36 and extend radially toward the axis of base plate 32. A top plate 37 of less diameter than base plate 32 is seated upon said base plate and is pivotally connected therewith by means of a screw threaded shaft 38, rigidly mounted upon top plate 37 and extended through an opening 39 in base plate 32. A nut 41 holds the two plates in rotatable engagement with respect to each other. Top plate 37 carries a corresponding number of contact members 43 rigidly mounted therein. The rearwardly extending ends of members 43 carry and are 85 electrically connected with hollow tubular contact members 44 for connection with lead wires 45, and the forwardly extending ends of said contact members 43 are rectangularly offset at 46 and extend radially away from the axis of top plate 37, so that the offset portions 36 and 46 may be brought into alignment with each other or laterally shifted with respect to each other, elongated curved slots 48 in base plate 32 being provided to permit a limited rotatable movement between the two disks 32 and 37. 90

The control and detecting device just described is connected in series with all spark plugs, see Figure 7 diagram which shows an ignition circuit similar to that shown in Figure 6. 100

When in operation the current flows from battery B' through coil C', from which coil a high tension current flows through lead 50, through distributor D' and thence in succession and timely, according to the position of distributor contacts, to the respective contact members 33, 43 of controlling and detecting device G, thence to the respective spark plugs H and finally through the ground (the motor body not shown) back to 110 coil C'. Rotation of disk 37 by means of its knob 51 regulates the spacing of the gaps between contact members or points 33, 34 of device G and the intensity of the spark at the plug gaps, in a manner similar to the operations of the preferred form of the invention. 115

Having thus described our invention, what we claim is:

A spark controlling and testing device for intensifying and visibly indicating the successive 120 sparking of the spark plugs of internal combustion engines, comprising a round base plate of insulating material, a plurality of contact members symmetrically secured to said base plate, a flanged disk of insulating material axially rotatably secured to said base plate, a metal plate seated within said flanged disk, lateral finger portions on said metal plate radially extending through openings in the flange of said disk for cooperation and alignment with said contact 125 members, said contact members and extensions being adapted to form variable spark gaps in a circuit, and means for connecting said contact members and said metal plate with the ignition circuit of an automobile. 130
